(57) **CLAIM**

We claim the ornamental design for a juice extractor, as shown and described.

DESCRIPTION

FIG. 1 is a front perspective view of a hot water dispenser showing our new design;

FIG. 2 is a front perspective view of the design of FIG. 1 showing the extension of a spout therefrom;

FIG. 3 is a front perspective view of the design of FIG. 1 showing the opening of a door on the top surface thereof;

FIG. 4 is a front view thereof;

FIG. 5 is a side view thereof;

FIG. 6 is a side view from the opposite side of FIG. 5;

FIG. 7 is a top plan view thereof; and,

FIG. 8 is an underneath plan view thereof.

The features of the design as claimed by applicants are shown in bold lines. The features shown in dotted lines are not claimed and are provided to indicate the context of the design. The rear view does not contain features of the design applicants intend to claim and is accordingly omitted.
